ADJUSTABLE SHELF UNIT

Minnetta Keeshen, Denver, Colo.

Application July 26, 1941, Serial No. 404,129

1 Claim. (Cl. 211—90)

This invention relates to shelf unit assemblies of a type wherein the elements are adapted for adjustment and variation in arrangement to meet specific requirements, and has as an object to provide an improved construction and arrangement of elements constituting such a unit.

A further object of the invention is to provide an improved construction and arrangement of elements constituting a shelf unit assembly adapted for use in either table or wall-bracket form.

A further object of the invention is to provide an improved construction and arrangement of elements constituting an adjustable shelf unit assembly susceptible of development in single or compound form to provide shelf space of varying capacity.

A further object of the invention is to provide an improved adjustable shelf unit susceptible of convenient assembly and disassembly and hence adapted for convenient storage, transportation, and variation to meet the requirements of specific use.

A further object of the invention is to provide a unit of the character described which is simple and inexpensive of manufacture, susceptible of development in a wide variety of specific forms, sizes, and materials, which is sturdy and durable in use, and which provides a maximum extent of available shelf area in proportion to the wall or floor space occupied by the unit.

My invention consists in the construction, arrangement, and combination of elements hereinafter set forth, pointed out in my claim, and illustrated by the accompanying drawing, in which—

Figure 1 is an isometric view of one embodiment and arrangement of my improved unit as assembled in compound form for use as either a table or wall bracket. Figure 2 is a cross section taken on the indicated line 2—2 of Figure 1. Figures 3, 4, 5 and 6 are front elevations of alternative combinations of the elements shown in Figure 1, whereby said elements are adapted to form compound shelf units fitted to specific requirements. Figure 7 is a front elevation of a shelf unit formed from certain of the elements illustrated in Figure 1 and adapted for use as a corner bracket.

The improved unit assembly, in any of its various forms and styles, is a combination of a number of identical shelf members with a plurality of identical risers or vertical stays rigidly interconnected with the shelf members to position the

latter in spaced, superposed relation in a single or compound, integrated, self-sustaining unit.

In the construction as shown, the shelf members are indicated by the numeral 10, and are shown as each consisting of a sector or quadrant bounded on two sides by straight margins intersecting at substantially right angles and on the third side by an arcuate margin intersecting the straight margins in smoothly-curved corners.

10 The shelf members 10 may be formed of any suitable material in any suitable or desired manner to provide rigid elements having smooth, plane upper surfaces adapted to function in the support of material and elements placed thereon, and such shelf members may conveniently and desirably be of wood or equivalent material, although a construction of such elements from metal is within the contemplation of the invention. Each of the straight margins of each shelf

15 member 10 is formed with an outwardly-opening, angular notch or recess 11 extending entirely through the vertical depth of the member 10 and inwardly from the margin of said member a distance equal to the thickness of the riser to be

20 associated therewith, and said notches 11 are located in each margin of a member 10 a like distance from the point of intersection of the notched straight margins, such distance being somewhat more than one-half of the length of 25 the straight margin measured from the point of straight margin intersection toward the junction of a straight margin with the curved outer margin.

Identical, notched, shelf members 10 are provided in such number as may be desired to form a particular shelf unit, and are assembled to 30 form the desired unit through engagement and connection with identical risers 12, each of which consists of a straight, slat-like element having a

35 cross section of a size to fit closely within and fill the notch 11 of a shelf member and a length suitable for development of the completed unit desired. The risers 12 are preferably rounded at each end and are provided with a plurality of 40 spaced holes 13 disposed along the longitudinal median line of each riser and extending entirely through the riser thickness.

45 Since the holes 13 are similarly positioned and spaced along each of the risers 12, it is convenient to arrange a number of shelf members 10 in parallel, spaced relation and in engagement 50 of their notches 11 with and about a pair of risers 12 and secure said shelf members in the relationship desired by means of screws 14, or like fastening elements, engaging through similarly-located

holes 13 in the respective risers, thereby completing a compact and rigid shelf unit assembly. It is, of course, essential that the shelf members 10 have a thickness or depth at their notches 11 sufficient to provide a substantial bearing surface engaging against side margins of the risers 12 received within said notches, in order that the shelf members will be held securely in position on the risers and thereby prevented from tilting about the screws 14 and away from a position perpendicular to the intersecting planes of the risers.

When two or more shelf members 10 are associated with and secured to two risers 12 in the manner shown and described, the resulting assembly is a corner bracket of the type illustrated in Figure 7, which is adapted for mounting in a corner formed by the perpendicular intersection of two walls, wherein the unit may be secured by means of nails or screws engaging through exposed holes 13 of the risers and with the walls. With this type of unit assembly, adjustment of the spacing between the shelves may be had by varying the number of intermediate shelf members, by varying the relative location of the intermediate shelf members, or by varying the relation between the extreme shelf members and the corresponding ends of the risers 12. In this type of unit it is desirable, although not essential, that the ends of the risers 12 lie in common planes perpendicular to their lengths, since no particular purpose is served by varying the upward or downward extension of one riser relative to the other.

Compound shelf unit assemblies susceptible of development through the use of additional shelf members 10 and risers 12 are formed by associating additional shelf members with one or the other of the risers employed in forming the simple unit assembly, and in supplying an additional riser in operative relation with the additional shelves, in the manner indicated in Figures 1, 2, 3, 4, 5 and 6. Where more than two risers are employed in a unit assembly, they may be arranged with their corresponding ends in either the same or different planes, according to the purpose for which the unit is to be employed or the effect to be produced. When the ends of the risers lie in common planes, the compound unit may function as a table, since the lower ends of the risers, being in the same plane, may engage the floor as a firm support for the assembly, but when the unit is to be used as a wall bracket, it may be desirable to stagger the ends of the risers, somewhat in the manner shown in Figure 4, for deco-

rative purposes. As is clearly indicated in the drawing, the shelf arrangement possible in the compound unit is almost infinitely variable, since the number and spacing of the shelf members 5 may be adjusted to meet varying specific needs and decorative schemes. While the shelf unit assemblies are illustrated throughout as comprising three shelf members in association with each pair of risers, it is to be understood that only 10 two shelf members are essential to complete a unit with each pair of risers and that additional shelf members may be employed in such number as may be desired and usable within the limitations imposed by the length of the risers and the 15 number of holes 13 provided therein.

The improved construction has particular advantage in that the elements of the assembly may be fabricated and shaped for shipment and storage in unassembled relation, no special tools or particular skill being necessary to complete the assembly of such elements. Further, the elements may be left in natural surface finish condition for subsequent painting, staining, or 20 enameling by the ultimate user to conform with 25 the desired decorative plans.

Since many changes, variations, and modifications in the specific form, construction, and arrangement of the elements shown and described may be had without departing from the spirit of 30 my invention, I wish to be understood as being limited solely by the scope of the appended claim, rather than by any details of the illustrative showing and foregoing description.

I claim as my invention:

An adjustable shelf unit comprising a plurality of identical shelf members formed with perpendicularly-related, straight, side margins each intersected at its midportion by an outwardly-opening notch, a pair of risers formed with spaced holes along their longitudinal, median lines fitted closely within and substantially filling corresponding notches of said shelf members to position the latter in superposed, spaced, parallel relation, means engaging through certain of said holes to removably connect each riser with each associated shelf member, additional, identical shelf members removably engaging with one of said risers by other means in other of said holes and thereby disposed in laterally-offset, parallel 40 relation with said first shelf members, and a third riser engaged within the notches of the otherwise free margins of said additional shelf members and removably connected therewith.
